VALVE TOOL

Barney McKenna, Hammond, Ind.

Application March 16, 1933. Serial No. 661,168

6 Claims. (Cl. 51—204)

This invention relates to an appliance which may be referred to as having reference to automotive repair practice, and it has more specific relation to a mechanical contrivance in the form of a simple and economical tool constructed for refacing the valve and reseating motor blocks in one operation without removing valves from the motor.

In carrying the inventive conception into practice I have evolved and produced a systematic arrangement of mechanical details assembled in an orderly manner and capable of practical and efficient use, the construction being such as to accomplish the simultaneous refacing and reseating operation above referred to and being capable of practical use for refacing valves after the same have been removed from the motor or reseating the motor block after the valves have been removed from said block.

20 Briefly stated, the form of the invention which I have adapted to accomplish my purpose is characterized by a rotary propulsion shaft with which a suitable source of power is connected, said shaft being constructed to accommodate a plurality of 25 circumferentially spaced adjustably mounted abrasive equipped parts susceptible of a single and double grinding operation.

The specific elements employed in this unique structural organization will become more readily 30 apparent from the following description and drawings.

In the drawings:

Figure 1 is a view in section and elevation showing the valve grinding tool and the manner 35 in which it is associated with a mushroom type valve.

Figures 2, 3 and 4 are sections on the line 2—2, 3—3 and 4—4 respectively of Figure 1.

Figure 5 is a detail sectional view of the adjustable means for regulating the cutter.

Referring now to the drawings in detail, and to Figure 1 in particular, it will be observed that the numeral 6 designates a mushroom valve of the type having a centering depression.

45 The rotary operating shaft of the improved grinding tool is generally denoted by the numeral 7 and is made up of an upper cylindrical screw-threaded portion 8 and a lower enlarged hexagonal body portion 9. In this bottom this portion 50 9 is formed with a socket containing a spring 10 which serves to project a pointed pilot pin 11 to allow the pin to be seated in the depression in the valve 6 for guidance purposes.

The body 9 is formed with longitudinally disposed slots 12 arranged at circumferentially

spaced points. The drive device embodies a universal joint 13 made up of suitably constructed and mated sections, with one section provided with a tang 14 to accommodate a chuck 15 of suitable construction from which the power is derived for rotating the complete shaft 7 and its universal joint drive 13.

In accordance with the inventive conception I provided three distinguishable grinding devices, these being arranged radially with respect to the shaft and at circumferentially spaced points, preferably one hundred and twenty degrees apart. Each grinding or abrasive device is the same in construction and a description of one will suffice for all. I therefore direct attention to Figure 1 70 wherein one complete device is illustrated.

In the first place, it embodies a substantially L-shaped adapter element indicated at 16 which is constructed to accommodate the elongated abrasive or grinding block 17. This element 16 includes a stem portion 18 and a substantially obtuse portion 19, the terminal of which is bifurcated to permit the furcations 20 to function as guides to straddle the stem of the valve. Particular attention is invited to the fact that the 80 abrasive block 17 is so fitted in the obtuse portion 19 as to protrude on opposite sides thereof whereby to enable it to have the duplex action of simultaneously grinding the valve 6 and the valve seat in the motor block (not shown).

It will be observed that the part 18 of the abrasive adapter is joined by connector links 21 to the body 9, the inner ends of the links 21 being pivoted in the adjacent slot 12, with their outer ends pivotally jointed to the adjacent end portions of the part 18. The part 18 is also partially maintained in position by a pivotally mounted adjusting link 22 whose upper end is pivoted between a pair of ears 23 on the longitudinally adjustable annulus or collar 24.

At this time I invite attention to Figure 5 where it will be observed that this collar is operatively connected with an adjusting nut having knurled plate finger grip 25 and a sleeve nut 26. This sleeve nut is internally and externally screw-threaded, the internal threads engaging the threaded shank 8 and the external threads serving to accommodate a retention nut 27. Thus the collar 24 is loosely confined between the nut 27 and the plate 25 to permit the requisite freedom of action and adjustment.

Under this arrangement the various abrasive grinding devices may be simultaneously raised and lowered to dispose the abrasive block 17 in the proper position with respect to the surfaces

adapted to be ground. In practice, the pilot pin 11 is seated in the existing centering depression of the valve 6 as shown in Figure 1 and the chuck 15 of the source of power (not shown) is attached to the stem 14. The universal joint drive 13 permits the required relative position of power with respect to the shaft 7 to provide for accommodation and effectiveness in operation and use.

10 The abrasive block devices may be adjusted for single action in grinding the bevelled edge of a mushroom valve or may be interposed between the valve and the seat in the motor block (not shown) without removing the valve, simultaneously reconditioning both the surfaces. Consequently it is possible with this device to grind the valve and motor block without removing the valve or to take out the valves and grind them or to reseat the motor block after the valves 20 have been removed.

It is thought that the description taken in connection with the drawings will enable a clear understanding of the invention to be had. Therefore, a more lengthy description is thought unnecessary.

While the preferred embodiment of the invention has been shown and described, it is to be understood that minor changes coming within the field of invention claimed may be resorted 30 to if desired.

I claim:

1. In a double and single acting resurfacing tool of the class described, a rotary propeller shaft, a valve grinding device embodying a substantially L-shaped adapter including a portion disposed alongside of and in substantial parallelism to the body portion of the shaft including an obtuse angular lower end portion having a slot and having its extremity bifurcated, the furcations constituting guides to straddle a valve stem and an abrasive block mounted in said slot and having opposite edge portions protruding beyond the slots for double acting resurfacing work, together with an adjustable and operating connection between said adapter and shaft.

2. In a tool of the class described, a rotary operating shaft having a screw-threaded shank and a body portion, said body portion being formed in one end with a socket, a spring-pressed pilot pin arranged in said socket, a power coupling device having universal connection with the screw-threaded shank and valve grinding means associated with said shank, and including an internal and externally threaded sleeve

nut, a retention nut carried by the external threads and a knurled finger adjusting disc.

3. In a valve grinder of the class described, a rotary propeller shaft having a polygonal body portion provided with a spring pressed pilot pin and a longitudinal slot, together with a screw-threaded shank, and an adjusting nut mounted for adjustment on said shank, a collar mounted loosely in said nut, a substantially L-shaped adapter device including an abrasive resurfacing element, a link connecting said device with said collar and additional connector links between said device and the slotted portion of said body.

4. A tool of the class described comprising a shank having a part at its lower end for engaging a part of a valve, a carrier member having a straight arm paralleling a part of the shank and a diagonally arranged arm, a grinder element carried by the last mentioned arm, links each having one end pivotally connected to the straight arm and its other end to a part of the shank, a member adjustable for vertical movement on the shank and a link pivoted to said member and to the upper end of the straight arm.

5. A device of the class described comprising a shank having a threaded portion, a pin at the lower end of the shank for engaging a recess in the upper face of a valve, a carrier member including a straight arm paralleling a part of the shank and a diagonally arranged arm, an abrasive block attached to the diagonal arm and projecting from opposite sides thereof, links pivotally connected to the straight arm and to parts of the shank, a nut threaded on the threaded part 105 of the shank, a collar rotatably arranged on the nut and a link connecting the collar with the upper end of the straight arm.

6. A device of the class described comprising a shank having a threaded portion, a pin at the lower end of the shank for engaging a recess in the upper face of a valve, a carrier member including a straight arm paralleling a part of the shank and a diagonally arranged arm, an abrasive block attached to the diagonal arm and projecting from opposite sides thereof, links pivotally connected to the straight arm and to parts of the shank, a nut threaded on the threaded part of the shank, a collar rotatably arranged on the nut, a link connecting the collar with the upper end 115 of the straight arm, the lower end of the diagonally arranged arm having a recess therein for receiving portion of the shank of a valve.
